UNITED STATES PATENT OFFICE

156,943

SPOON OR SIMILAR ARTICLE

Edmund A. Davis, Attleboro, Mass., assignor to Edith E. Steckler, St. Martinville, La.

Application August 27, 1949, Serial No. 4,719

Term of patent 14 years

(Cl. D54—12)

To all whom it may concern:

Be it known that I, Edmund A. Davis, a citizen of the United States, residing in the city of Attleboro, county of Bristol, and Commonwealth of Massachusetts, have invented a new, original, and ornamental Design for a Spoon or Similar Article, of which the following is a specification, reference being had to the accompanying drawing, forming a part thereof.

Fig. 1 is a front elevational view of a spoon embodying my new design; and

Fig. 2 is a rear view thereof.

I claim:

The ornamental design for a spoon or similar article, substantially as shown.

EDMUND A. DAVIS.
